His Attorney.

UNITED STATES PATENT OFFICE.

JACOB W. McNAIRY, OF SCHENECTADY, NEW YORK, ASSIGNOR TO GENERAL ELECTRIC COMPANY, A CORPORATION OF NEW YORK.

AUTOMATIC RECLOSED CIRCUIT-BREAKER SYSTEM.

Application filed October 3, 1924, Serial No. 741,496. Renewed October 8, 1928.

My present invention relates to automatic reclosing circuit breaker systems and apparatus and particularly to such systems where in an automatic circuit breaker is held in the closed position by normally energized electrical means and is arranged to operate sequentially with other switching apparatus in controlling electric circuits.

The invention has for its object the provision in a system of the above character of a novel arrangement of control apparatus and circuits for increasing the holding force of the electrical means during the closure of the circuit breaker and until after the operation of the other switching apparatus.

In the co-pending joint patent application Serial No. 683,533, filed Dec. 31, 1923, by John F. Tittle and myself, there is disclosed and broadly claimed a control system and apparatus whereby the attractive force of the holding electromagnet of a circuit breaker which is electromagnetically held in the closed position may be increased during the closure of the breaker in order to prevent the accidental opening thereof due to the jar or shock necessarily accompanying the closing operation. In the particular embodiment illustrated in the above application, the increase in the attractive force of the holding electromagnet during closure of the breaker is effected by a manually operated push button which is arranged to establish a shunt circuit around a resistance in circuit with the normally energized holding electromagnet and at the same time to effect the operation of the closing mechanism of the breaker.

When such a circuit breaker is arranged to operate sequentially with other automatic switching apparatus, as for example in automatic reclosing circuit breaker systems such as described and claimed in the Anderson Patent No. 1,546,879, issued July 21, 1925, and the McDonald Patent No. 1,534,724, issued April 21, 1925, both of which are assigned to the same assignee as my present invention, it is desirable that the over excitation of the holding electromagnet be continued automatically until after the operation of the other switching apparatus has been effected in order to prevent the accidental or premature opening of the breaker. Otherwise the breaker may be opened out of proper sequence, particularly when the breaker is subjected to a current surge near

the tripping value by the operation of the other switching apparatus.

My present invention provides a simple and reliable arrangement of control apparatus and circuits whereby the holding electromagnet of the breaker may be over excited until after the operation of the other switching apparatus has been effected in such automatic reclosing systems although the invention is not necessarily limited thereto.

A better understanding of the invention may be had from the following description of the accompanying drawing in which Fig. 1, diagrammatically illustrates the invention embodied in an automatic reclosing circuit breaker system for controlling a feeder circuit and Fig. 2, is a circuit diagram of an automatic load limiting protective system for a dynamo electric machine likewise embodying the invention.

The novel features and combinations which I believe to be characteristic of my invention are pointed out with particularity in the appended claims.

Referring to Fig. 1 of the drawing, power is supplied from the supply line 10 to the feeder line 11 which is connected through an electrical translating device T, such as a motor, transformer, or the like, to ground. The power supply circuit extends through the overload circuit breaker 12 which is biased to the open position in which it is shown and is electromagnetically held in the closed position by a normally energized holding electromagnet 13. In the preferred form shown, the circuit breaker 12 is of the high speed trip free type described and claimed in the Tittle Patent No. 1,560,440, issued November 3, 1925, and assigned to the same assignee as my present invention although other types of circuit breakers may be employed if desired. Circuit breaker 12 as illustrated, is operated to the closed position by a closing electromagnet 14 and is provided with a bucking bar 15 which is arranged to effect the opening of the breaker automatically upon the occurrence of overload or short circuit conditions on the feeder line 11. The automatic reclosure of breaker 12 is accomplished upon the recurrence of normal operating conditions on the feeder line 11 by automatic control means comprising a feeling out contactor 16, a discriminating relay 17, and the time element relays 18 and 19, which are arranged to oper-

ate in the manner disclosed in the previously mentioned Anderson patent. As will be more fully described hereinafter in connection with the operation of my invention, the arrangement is such that the feeling out contactor 16 is closed only when the circuit breaker 12 is in the open position and is opened upon the closure of breaker 12 by means of auxiliary contact mechanism with which the latter is provided.

In order to increase the energization of the holding electromagnet 13 during the closure of breaker 12 and until after the resulting operation of the feeling out contactor 16 to the open position, the resistor 20 is connected in circuit with the energizing winding of electromagnet 13 and is arranged to be short circuited by means jointly controlled by the breaker 12 and contactor 16 in a manner which will be better understood from a description of the operation of my invention which is as follows:

Assuming that the supply line 10 is energized from a suitable source of supply such as illustrated and that the breaker 12 has been operated to the open position in which it is shown in response to an overload on the feeder line 11, an energizing circuit for the time delay relay 18 is established from the supply line 10 through the auxiliary contact 21 of feeling out contactor 16, the auxiliary contact 22 of circuit breaker 12, through the operating winding of relay 18 and the lower contact 23 of discriminating relay 17 to ground. After a time interval, time element relay 18 closes its contact 24 and opens contact 25, thereby establishing energizing circuits through the contact 24 for both the time element relay 19 and the feeling out contactor 16, the circuit of the latter extending through the auxiliary contact 26 of breaker 12 and the voltage reducing resistor 27. Contactor 16 at once closes and connects the feeder line 11 to the supply line 10 through the current transformer 28 and the feeling out resistance 29 which is proportioned to maintain the resulting current flow within desirable limits. The time relay 19, however, requires a certain period for operation of its contact to the closed position after the feeder line 11 is connected to the supply line 10 through the feeling out resistor 29. This permits the selective operation now to be described to occur.

It will be observed that the operating winding of discriminating relay 17 is connected to be energized from the current transformer 28 and thus is energized responsively to the rate of change of current in the feeling out circuit. If the rate of change of current exceeds a predetermined value, the relay 17 operates its circuit controlling contacts, 23 and 30 from the closed position to the open position wherein they are mechanically held by the latch 31. Upon the opening of contact 23, the energizing circuit of time element re-

lay 18 is interrupted and the latter immediately returns to the position in which it is shown, thereby opening the energizing circuit of both time element relay 19 and feeling out contactor 16, each of which also returns to the position shown. At the same time the reclosure of contact 25 of time element relay 18 establishes an energizing circuit for the resetting electromagnet 32 of the discriminating relay 17 extending from supply line 10 through the contacts 21 and 22, the resistance 33, contacts 25, and the winding of electromagnet 32 to ground. The resulting energization of electromagnet 32 releases latch 31 thereby permitting the contacts of discriminating relay 17 to return to the position in which they are shown.

The reclosure of contact 23 again energizes the time element relay 18 and the latter after the time interval required for closure of contact 24 effects the energization of both feeling out contactor 16 and time element relay 19 in the manner previously described. Thereupon the feeling out contactor 16 reconnects the feeder line 11 to the supply line 10 through the current transformer 28 and the feeling out resistance 29 as previously described.

If the overload or short circuit on the feeder line 11 had been removed so that the resulting rate of change of current through the transformer 28 is below the value at which the discriminating relay 17 is adjusted to pick up its contacts 23 and 30, the relay 18 will be maintained closed and consequently the time element relay 19 will be maintained energized through the contact 24 of relay 18 for a sufficient time interval for the time element relay 19 to operate its contact to the closed position. Upon closure of the contact of time element relay 19 the operating winding of reclosing relay 34 is connected in shunt with the resistance 20 through a circuit extending from the grounded end of the resistance 20 through the auxiliary contact 35 of feeling out contactor 16, the contact of time element relay 19, and the winding of relay 34 to the other end of the resistance 20. This energizes the reclosing relay 34 responsively to the voltage drop across the resistance 20 and the additional current flowing through the winding of relay 34 increases the energization of the holding electromagnet 13 of circuit breaker 12. The resistance 20 is in a series circuit with the operating winding of the normally energized holding electromagnet 13 extending from the supply line 10, through the winding of the holding electromagnet 13 and thence through the resistance 20 to ground. The resistance 20 thus serves to limit the energizing current of the holding electromagnet 13 which flows in the series circuit. However, when the operating winding of relay 34 is connected in multiple with the resistance 20, this provides a shunt path around the resistance 20 and permits more energizing cur-

- rent to flow through the winding of electromagnet 13 and in this way increases the energization of the holding electromagnet. Upon the resulting closure of relay 34, the closing electromagnet 14 of breaker 12 is energized directly from the supply lines 10 and immediately operates the breaker 12 from the open position in which it is shown to an intermediate position in which the movable magnetic armature 35 is held by the holding electromagnet 13 with however the circuit controlling contacts 36 and 37 of the breaker disengaged. Due to the trip free feature of the Tritle type of circuit breaker, the contacts 36 and 37 are maintained disengaged until after the de-energization of the closing electromagnet 14 which is accomplished in the following manner.
- During the operation of circuit breaker 12 to the intermediate position, the auxiliary contacts 22, 26 and 38, associated therewith are operated in the following manner. Contact 22 is disengaged from the left hand stationary contacts co-operating therewith, thus deenergizing the time element relay 18. At substantially the same time contact 26 is opened and contact 38 closed to connect the winding of the feeling out contactor 16 in shunt circuit with the feeling out resistor 29. Also contact 22 is brought into engagement with the right hand stationary contacts thereby entirely short circuiting the resistance 20 as well as the operating winding of relay 34, the shunt circuit in each case extending through the contact 35 on the feeling out contactor 16. The short circuiting of resistor 20 causes the holding electromagnet 13 to be further over-excited by reason of the full voltage of supply line 10 being impressed thereupon. The short circuiting of the winding of relay 34 causes this relay to open. Upon the opening of relay 34 the energizing circuit of closing electromagnet 14 is interrupted and the latter returns to the position in which it is shown thus permitting the circuit controlling contacts 36 and 37 to engage and complete the circuit through which feeder line 11 receives power from the supply line 10.
- During the closure of breaker 12, the operating winding of feeling out contactor 16 is connected in shunt with the feeling out resistance 29 through the auxiliary contact 38 which is arranged to close slightly before or simultaneously with the opening of contacts 22 and 26 as previously described. Thus with the feeder line 11 connected to an appreciable load, contactor 16 is maintained energized responsively to the voltage drop across resistance 29, while with no appreciable load, the resistance 29 serves as a low resistance shunt for the winding of contactor 16 and thereby delays the opening of this contactor by preventing the rapid decay of the flux thereof. In this way the feeling out contactor 16 is maintained closed so as to insure that the holding electromagnet 13 is maintained over-excited by the short circuiting of resistance 20 until after the engagement of the circuit breaker contacts 36 and 37. The closing of the contacts of the circuit breaker establishes a short circuit around the feeling out resistance 29. The short circuiting of resistance 29 due to closure of the circuit breaker contacts also serves to short circuit the operating winding of feeling out contactor 16. As soon as the decay of flux in the short circuited winding of the feeling out contactor 16 permits, this contactor returns to the open position and interrupts the short circuit around the resistance 20 by the opening of auxiliary contact 35. With the resistance 20 again inserted in circuit with the winding of holding electromagnet 13, the energization thereof is reduced to the normal value and circuit breaker 12 again is in condition to afford the normal overload protection for feeder line 11 for which the breaker is calibrated.
- It will be evident that by over exciting the holding electromagnet 13 in the manner just described, the accidental or premature opening of the breaker due to jars, shocks or current surges near the tripping value occurring during the closing operation thereof and until after the feeling out contactor has opened, is effectively prevented.
- Referring now to Fig. 2 which illustrates the invention embodied in an automatic load limiting protective system for a dynamo electric machine such as the direct current generator 40, it will be observed that a high speed, trip free circuit breaker 12 of the Tritle type previously described is connected in the negative side of a direct current generator 40 and is arranged to operate sequentially with the line contactor 41 in protecting the generator from overload or short circuit current. The load limiting resistors 42 and 43 are connected in the circuit through which generator 40 supplies power to the supply line 10 and the resistor 42 is of suitable ohmic value to maintain the current supplied by generator 40 within desirable limits upon a moderate overload on supply line 10 while the resistor 43 is of such ohmic value as to effectively prevent flashover of the generator 40 on a heavy overload or even under short circuit conditions. A short circuit around the load limiting resistor 42 is controlled by the electromagnetic switch 44 which in turn is controlled under moderate overload conditions by the overload relay 45 and the resistor 43 is arranged to be short circuited when the circuit breaker 12 is closed and is inserted in the generator circuit upon the opening of the breaker.
- Line contactor 41 is electrically interlocked with the circuit breaker 12 so that the former is operated to the open position after the opening of breaker 12 and is operated to the

closed position after the closure of breaker 12. In order to prevent the accidental opening of circuit breaker 12 during the closing operation thereof as well as the premature opening thereof upon the occurrence of a temporary current surge when the line contactor 41 is closed, the holding electromagnet 13 of breaker 12 is arranged to be over-excited during the closure of breaker 12 and until contactor 41 has been operated to the closed position. The manner in which this is accomplished will be more clearly understood from a description of the operation of the automatic load limiting system embodying my invention which is as follows:

Assume that the high speed circuit breaker 12 has opened responsive to a heavy overload on supply line 10 and inserted the current limiting resistor 43 in circuit to prevent a flashover on the commutator of the generator 40 and that consequently the switch 44 has opened and contactor 41 has been operated to the open position to disconnect the generator 40 from the supply line 10. With the contactor 41 and the switch 44, in their respective open positions as shown, the winding of reclosing relay 34 is connected in shunt with the voltage reducing resistance 20 through a circuit extending from the grounded end of resistance 20 through the auxiliary contact 46 of line switch 41, the auxiliary contact 47 of switch 44, and the operating winding of relay 34 to the other end of resistance 20. This both energizes the reclosing relay 34 and over-excites the holding electromagnet 13 of breaker 12. Upon response of relay 34, the closing electromagnet 14 of breaker 12 is connected across the armature of generator 40 and the current limiting resistance 43 in series circuit and is thereby energized to operate the breaker and carry the movable magnetic armature 35 into engagement with the holding electromagnet 13. The resulting operation of breaker 12 closes the auxiliary contacts 48 and 49 and the former establishes a short circuit around the operating winding of the closing relay 34 as well as around the resistance 20 thus de-energizing the relay and further over-exciting the holding electromagnet 13. Contact 49 connects the operating winding of line contactor 41 to the ungrounded terminal of the closing electromagnet 14 but until the contacts of the reclosing relay 34 are opened, the contactor 41 is not energized since the operating winding thereof is connected between points of equal potential. Upon the opening of the contacts of reclosing relay 34 and the consequent de-energization of the closing electromagnet 14, the energization of the operating winding of line contactor 41 is further delayed due to the voltage induced by the decaying flux in the closing electromagnet 14. Thus the energization of line switch 41 is delayed until after the

engagement of the circuit controlling contacts 36 and 37 of breaker 12. Thereupon the current flowing through the operating winding of line contactor 41 and the operating winding of closing electromagnet 14 in series circuit is sufficient to operate the former to close its contact but is insufficient to operatively energize the closing electromagnet 14 since the winding of the latter is of relatively low resistance. 75

When the line switch 41 finally responds to connect the generator 40 with the current limiting resistance 42 in circuit therewith to the supply lines 10, the auxiliary contact 46 is opened thereby interrupting the shunt circuit around the resistance 20. This reduces the energization of holding electromagnet 13 to the normal value and the breaker 12 is again responsive to open upon the overload current for which it is adjusted. 80

Upon the closure of line contactor 41, a circuit is established from the supply line 10 through the operating winding of resistance controlling switch 44, the contact 50, the voltage reducing resistance 51, the contacts of current relay 45, the auxiliary contact 49 of breaker 12, and the winding of closing electromagnet 14 to ground. Thus the switch 44 is placed under the control of the current relay 45 and the load limiting resistor 42 is 90 maintained in circuit with the generator 40 when the current supplied by the latter to supply line 10 is above the predetermined value at which the current relay contacts are opened and is short-circuited when the generator current decreases below the predetermined value at which the current relay 45 closes its contact and energizes the switch 44. 100

Should a heavy overload or short circuit then occur on the supply line 10 as was initially assumed, the circuit breaker 12 immediately operates to insert the current limiting resistor 43 in the generator circuit and at the same time to open the circuit controlled by auxiliary contact 49 through which both line contactor 41 and resistance controlling switch 44 are energized. The automatic reclosure of the breaker and line contactor 41 is effected in the manner previously described with the holding electromagnet 13 of the former over-excited until after closure of the latter. 110

In accordance with the patent statutes, I have described the principle of operation of my invention together with the apparatus which I now consider to represent the best embodiment thereof, but I would have it understood that the apparatus shown is only illustrative and that the invention may be carried out by other means. 120

What I claim as new and desire to secure by Letters Patent of the United States is:—

1. In an automatic reclosing circuit breaker system the combination of an automatic circuit breaker having normally energized elec- 130

trical means for holding the breaker in the closed position, an electromagnetically operated switch controlled by said breaker and arranged to be operated to one position after the 5 opening of the breaker and to another position after the closure of the breaker, and means jointly controlled by said breaker and said switch for increasing the holding force of said first means during the closure of the 10 breaker and until after the said switch is operated to the said other position.

2. In an automatic reclosing circuit breaker system, the combination of an automatic circuit breaker having a normally energized 15 electromagnet for holding the breaker in the closed position, a resistance in circuit with said electromagnet, an electromagnetically operated switch controlled by said breaker and arranged to be operated to one position 20 after the opening of the breaker and to another position after the closure of the breaker, and connections jointly controlled by said breaker and said switch for short circuiting said resistance during the closure of the breaker 25 and until the said switch is operated to the said other position.

3. In an automatic reclosing circuit breaker system, the combination of an automatic circuit breaker having electroresponsive closing 30 means and independent normally energized electrical means for holding the breaker in the closed position, an electromagnetically operated switch connected to be controlled by said breaker and arranged to be operated to one 35 position after the opening of the breaker and to another position after the closure of the breaker, and means jointly controlled by said breaker and said switch for energizing the said closing means and simultaneously increasing the holding force of said holding 40 means during the closure of the breaker and until after the electromagnetically operated switch is operated to said other position.

4. In an automatic reclosing circuit breaker 45 system, the combination of an automatic circuit breaker having a closing electromagnet and an independent normally energized electromagnet for holding the breaker in the closed position, a resistor in circuit with said 50 holding electromagnet, an electromagnetically operated switch connected to be controlled by said breaker and arranged to be operated to one position after the opening of the breaker into another position after the closure of 55 the breaker, and connections jointly controlled by said breaker and said switch for energizing the closing electromagnet and short circuiting said resistor during the closure of the breaker and until after the said 60 switch is operated to said other position.

5. In an automatic reclosing circuit breaker system, the combination of an automatic circuit breaker having a closing electromagnet and a normally energized holding elec-

tromagnet, a resistance in circuit with said holding electromagnet, an electromagnetic switch arranged to cooperate with said breaker in controlling a circuit, switch mechanism and connections whereby the closing electromagnet of said breaker and the operating winding of said switch are sequentially energized and de-energized and connections jointly controlled by said breaker and said switch for controlling said resistance to increase the energization of said holding electromagnet simultaneously with the de-energization of said closing electromagnet. 65 70 75

6. In an automatic reclosing circuit breaker system, the combination of an automatic circuit breaker having a closing electromagnet and a normally energized holding electromagnet, a resistance in circuit with said holding electromagnet, an electromagnetic switch arranged to cooperate with said breaker in controlling a circuit, means associated with 80 said breaker and arranged to control the energization of said switch to operate the same to one position when the breaker is opened and to another position when the breaker is closed, an auxiliary switch mechanism associated with 85 said breaker and with said switch and connections jointly controlled thereby for short circuiting said resistance to increase the energization of said holding electromagnet during the closure of the breaker and until the 90 95 said switch is operated to said other position.

7. In an automatic reclosing circuit breaker system, the combination with an automatic circuit breaker having a closing electromagnet and a normally energized holding electromagnet, an electromagnetic switch controlled by said breaker and arranged to be operated to one position after the breaker is opened and to another position after the breaker is closed, connections whereby the said closing electromagnet is energized to close the breaker when the said switch is in said one position, and means jointly controlled by said breaker and said switch for de-energizing said closing electromagnet and increasing the energization 100 105 110 of said holding electromagnet during the closure of the breaker.

8. In an automatic reclosing circuit breaker system, the combination with an automatic circuit breaker having a closing electromagnet and a normally energized holding electromagnet, a resistance in circuit with said holding electromagnet, an electromagnetic switch associated with said breaker and arranged to be operated to one position after the breaker is open and to another position after the breaker is closed, an electromagnetic relay for connecting the said closing electromagnet to a source of power, and connections jointly controlled by said breaker and said switch for energizing the winding of said relay in shunt with said resistance upon the operation of said switch to said one position and for short cir- 115 120 125

cuiting the said relay and said resistance upon the closure of the breaker and until after operation of said switch to said other position.

9. In an automatic reclosing circuit breaker system, the combination of an automatic circuit breaker having a closing electromagnet and a normally energized holding electromagnet, an electromagnetic switch controlled by said breaker and arranged to be operated to one position upon the opening of the breaker and to another position upon closure of the breaker, and connections jointly controlled by said breaker and said switch for simultaneously energizing said closing electromagnet and increasing the energization of said holding electromagnet when the breaker is opened and said switch is in said one position and for de-energizing the said closing electromagnet and maintaining the said holding electromagnet over-energized during the closure of the breaker and until after the said switch is operated to the said other position.

10. In an automatic reclosing circuit breaker system, the combination of an automatic circuit breaker having a closing electromagnet and a normally energized holding electromagnet, electromagnetic switch mechanism for controlling said breaker and arranged to be set into operation upon the opening of the breaker for energizing said closing electromagnet to reclose the breaker, and to be set into operation upon the closure of the breaker to return to its initial position, and means jointly controlled by said breaker and said electromagnetic switch mechanism for increasing the holding force of said holding electromagnet during the closure of the breaker and until after the said switch mechanism has returned to its initial position.

40 11. In an automatic reclosing circuit breaker system, the combination of an automatic circuit breaker having a closing electromagnet and a normally energized holding electromagnet, electromagnetic means set into operation upon the opening of the breaker for energizing said closing electromagnet responsive to the electrical condition of the circuit controlled by said circuit breaker and comprising a resistor and an electromagnetic switch for connecting said resistor in shunt with the circuit controlling contacts of said circuit breaker when the same are in the open

position and for interrupting the said shunt circuit upon the closure of the breaker, and means jointly controlled by said switch and said circuit breaker for increasing the holding force of said holding electromagnet during the closure of the breaker and until after the said switch has operated to interrupt the said shunt circuit.

55 12. In an automatic reclosing circuit breaker system, the combination of a circuit having a current limiting resistance connected therein, an automatic circuit breaker for short-circuiting said resistance and having a closing electromagnet and a normally energized holding electromagnet, an electromagnetic switch controlled by said breaker and arranged to open said circuit upon the opening of said breaker and to close said circuit 60 upon the closure of said breaker, and means jointly controlled by said breaker and said switch for increasing the holding force of said holding electromagnet during the closure of the breaker and until after the said switch has operated to close said circuit.

65 13. In an automatic reclosing circuit breaker system, the combination of a circuit having a current limiting resistor connected therein, an automatic circuit breaker for controlling 70 a short circuit around said resistance and having a closing electromagnet and a normally energized holding electromagnet, a resistance in circuit with said holding electromagnet, an electromagnetic switch controlled by said breaker and arranged to be operated to open said circuit upon the opening of the breaker and to close said circuit upon the closure of the breaker, and connections jointly controlled by said switch and said breaker for 75 simultaneously controlling said second resistance to increase the energization of said holding electromagnet and energizing said closing electromagnet when said breaker and said switch are in their respective open positions and for de-energizing said closing electromagnet and maintaining the said holding electromagnet over-energized during the closure of the breaker and until after closure of 80 said circuit.

85 90 95 100 In witness whereof, I have hereunto set my hand this 2nd day of October, 1924.

JACOB W. McNAIRY.
